CLAIM

The ornamental design for a gate end cap, as shown and described.

DESCRIPTION

FIG. 1 is a top, front, left side perspective view of a gate end cap showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The long-dash short-dash broken lines in the figures represent boundaries of the claimed design and form no part thereof. All other broken lines illustrate portions of the gate end cap that form no part of the claimed design.
